ATTORNEY

UNITED STATES PATENT OFFICE.

ROBERT C. KERR, OF READING, MICHIGAN.

FOLDING CHAIR.

1,257,877.

Specification of Letters Patent. Patented Feb. 26, 1918.

Application filed November 4, 1915. Serial No. 59,515.

To all whom it may concern:

Be it known that I, ROBERT C. KERR, a citizen of the United States, residing at Reading, county of Hillsdale, State of Michigan, have invented a certain new and useful Improvement in Folding Chairs, and declare the following to be a full, clear, and exact description of the same, such as will enable others skilled in the art to which it pertains to make and use the same, reference being had to the accompanying drawings, which form a part of this specification.

This invention relates to folding chairs. This chair is so constructed and arranged to fold that the folding parts are all substantially included within the uprights when the chair is folded up, and hence there are no protruding parts and the chairs may be very easily and neatly stacked. This will more fully appear as the various devices are described.

In the drawings,—

Figure 1 is a front elevation of the chair set up. Fig. 2 is a vertical section showing in dotted lines the positions assumed by the parts as the chair is being folded up. Fig. 3 is a vertical section of the folded chair showing how the parts are neatly contained all within the uprights. Fig. 4 is an underneath view of one pair of meeting corners of the seat bottom and seat back. Fig. 5 is a detail of one of the links that connect the seat bottom with the seat back. Fig. 6 is a detail view of one corner of the seat bottom showing how the spring link locks the parts together.

The uprights are designated *a* and comprise a pair of rails which are connected together at the top by a wooden bar *b* which acts as part of the seat back when the chair is in open position. The metal cross rod *c* connects and braces the rails at their mid portion while near the bottom the rails are provided with a wooden cross shaft *d*. Upon this cross shaft is pivoted a pair of legs *e* to the inside of the uprights *a*.

The seat back *g* is pivoted at its top on the inside of the uprights as indicated at *h*. These pivots are steel gudgeons provided with integral washers to prevent binding. The seat bottom *i* is removably pivoted with-

in the uprights and at its sides slightly distant from its rear edge in the obliquely-extending slots *j* of the uprights. Similar gudgeons are used for this purpose. The purpose of this obliquely-disposed slot is to throw the seat back and seat bottom out at the back and dispose them in an angular relation which is very comfortable for the user of the chair, while, when the parts are folder together the oblique disposition of the slots brings the seat back and the seat bottom into such a relation with the uprights that they are both contained wholly within the edges of the uprights. This might perhaps be accomplished by a slot parallel with the side edges of the uprights, but it would be located so close to the front edge of the upright and separated by so small an amount of wood as to soon split out at the bottom where the greatest stress is received when the chair is bearing a load.

The pivot pins or gudgeons which movably pivot the seat bottom in this oblique slot also pivot one end of the links *k*, the other ends of which are pivoted to the outside of the legs *e* near their tops.

The lower edges of the side rails of the seat back and the seat bottom are pivoted so that when the chair is opened out, as shown in Fig. 2, the ends of these side rails come together in a tight joint as shown in this figure. The meeting ends of these side rails of the seat back and seat bottom are slotted to receive the link *l* by which the seat back and seat bottom are hinged together.

It will be noted that the rear edges of the legs are notched as at *m* so that they straddle the brace rod *c* when in folded position as shown in Fig. 3.

When the chair is in opened out position, by reason of the arrangement of parts as already described, the seat back and seat bottom assume a very comfortable position with respect to the uprights, the two projecting slightly back of the plane of the uprights so as to position the sitter in the correct sitting position. When the chair is folded, the seat bottom can be grasped at the front and folded up to the position shown in the dotted lines of Fig. 2. The

link *k* pivoted to the seat bottom draws the pair of legs in toward a parallel position with respect to the side rails as shown in the dotted lines of Fig. 2. Continuing to 5 move the seat bottom toward the seat back, the seat bottom finally reaches the position shown in Fig. 3, where it is parallel with the uprights and contained wholly within the edges of the uprights, as is also the pair of 10 legs *e*. The seat bottom by reason of being hinged to the seat back by the links *l* likewise draws the seat back in parallel with the side rails. It will be noted that the link *l* is rigidly attached to the seat bottom and 15 pivots to the seat back. The purpose of this is to lift the seat bottom somewhat above the seat back when the parts are folded parallel as shown in Fig. 3. This is important for the reason that it makes room 20 for the legs *e* to fold in under the seat back and seat bottom, which would not otherwise be possible for the reason that the top of the legs would strike the downwardly-protruding ends of the side rails of the seat 25 bottom.

The links *k* are provided with pressed-in recesses *y* which snap over the heads of the pins *z* (Fig. 6) in the side rails of the seat bottom when the chair is folded. This provides adequate means to hold the parts in folded position until it is desired to set up 30 the chair for use, whereupon the parts by a slight pull may be disengaged.

What I claim is:

35 1. A folding chair, having in combination, a pair of uprights, means for connecting and bracing the same, a seat back pivoted near its top to the inside of the uprights, a seat bottom hingedly connected 40 to the seat back and movably pivoted in the inside of the uprights, said uprights being provided with a pair of obliquely-extending slots for guiding said pivots of the seat bottom and located near the longitudinal 45 center of the uprights at the bottom and extending obliquely toward the edges of the uprights as they extend upward, a pair of legs pivoted to the inside of the uprights, and means between the seat bottom and the 50 legs for drawing the legs in parallel with the side rails when the seat back and seat bottom are folded parallel with the uprights.

2. A folding chair, having in combination, a pair of uprights provided with slots, 55 means for connecting and bracing the same, a seat back pivoted near its top to the inside of the uprights, a seat bottom movably pivoted in said slots of the uprights and hingedly connected at its back with the 60 bottom edge of the seat back, a pair of legs pivoted inside of the side rails, and a link extending from the said pivots of the seat bottom and uprights and pivoted to the legs 65 for the purpose of drawing the legs in par-

allel with the uprights when the seat back and seat bottom are folded up into parallel relation with respect to the uprights.

3. A folding chair, having in combination, a pair of uprights provided with upwardly-extending slots, a seat back pivoted near its top inside the uprights, a seat bottom movably pivoted in said upwardly extending slots, so that the front edge in the folding takes the upper position and the 70 rear edge takes the lower position, links connecting the seat bottom and seat back at their meeting edges, a pair of legs pivoted inside of the uprights, and a draft connection between the seat bottom and pair 75 of legs for drawing the legs in parallel relation with the uprights when the seat bottom and seat back are folded parallel with the uprights.

4. A folding chair, having in combination, a pair of uprights provided with upwardly-extending slots, a seat back pivoted near its top to the inside of the uprights, a seat bottom movably pivoted in said upwardly-extending slots of the uprights by 80 projecting pins, a pair of links connecting the meeting edges of the seat back and seat bottom and having a rigid connection to the latter, a pair of chair legs pivoted inside of the uprights, and a pair of links pivoted 85 at one end on the projections which engage in the upwardly-extending slots and pivoted at the other end to the tops of the legs. 90

5. A folding chair, having in combination, a pair of uprights, means for connecting and bracing the same, said uprights being provided with upwardly-extending slots, a seat back pivoted near its top on the inside of the uprights, a seat bottom movably pivoted in said upwardly-extending 100 slots by projecting pins, a pair of links connecting the meeting edges of the seat bottom and seat back and engaging in slots in each, a pair of legs pivoted inside the uprights, and a pair of links pivoted at one 105 end on the projecting pins of the seat bottom and at the other end pivoted to the tops of the pair of legs.

6. A folding chair, having in combination, a pair of uprights, a seat back secured 110 thereto, a seat bottom pivoted to the uprights, a pair of legs pivoted to the uprights, one or more links connecting the legs with the seat bottom and provided with one or more snap-recesses, and projecting heads on the side of the seat bottom over which the said snap-recess or recesses 115 may engage to lock the parts in folded position.

7. A folding chair, having in combination, a pair of uprights connected together in parallel position, said uprights being provided with longitudinally-extending slots on their insides, a seat back at its top pivoted to the uprights, a seat bottom at 120 125 130

its rear hinged to the bottom of the seat back and intermediate its rear and front edges provided with projecting pivots from its sides that run in the longitudinal slots of the uprights, a pair of legs pivoted to said uprights and arranged to have their upper ends engage under the seat bottom, and

links pivoted on the said pivots in the sides of the seat bottom and secured at their outer ends to the upper ends of the seat legs.

In testimony whereof, I sign this specification.

ROBERT C. KERR.
